UNITED STATES PATENT OFFICE

2,514,763

MOP HOLDER HAVING SCREW OPERATED
SLIDING JAWThomas W. Healy, Rochester, N. Y., assignor of
one-half to Nicholas Grzymkowski, Rochester,
N. Y.

Application November 19, 1946, Serial No. 710,753

3 Claims. (Cl. 15—153)

1

The object of this invention is to provide a new improved form of mop and mop handle.

Another object of the invention is to form the mop handle with two sleeves, one having a male thread and the other having a female thread which threads engage each other for the purpose of opening or closing the jaws of the mop.

Another object of the invention is to form a male sleeve with a jaw swiveled thereon which slides in and engages with the yoke that is attached to the female sleeve.

Another object of the invention is to permit the two sleeves to be fully turned on each other and locked in engagement with each other in any desired position.

These and other objects of the invention will be illustrated in the drawings, described in the specification and pointed out in the claims at the end thereof.

In the drawings:

Figure 1 is an assembly showing the mop stick and the mop handle.

Figure 2 is a detail view of the mop stick and the male sleeve with the male thread thereon, fastened to the mop stick.

Figure 3 is a sectional view on the line 3x—3x of Figure 1 looking down in the direction of the arrow.

Figure 4 is a section on the line 4x—4x of Figure 1 looking down in the direction of the arrow.

Figure 5 is a horizontal section through the mop stick on the line 5x—5x of Fig. 1 showing the assembly of the two sleeves and the locking device therefor in top plan view.

Figure 6 is a side elevation of the male sleeve partly broken away above and below with the female sleeve positioned thereon and also partly broken away with the reinforcing band and the locking block therefor in position on the male sleeve.

Figure 7 is a side elevation of a part of the male sleeve and a part of the female sleeve with a modified form of the locking device between the two sleeves thereon.

Figure 8 is a diagrammatic view of the female sleeve and the yoke with the upper jaw in process of being inserted in the yoke.

Figure 9 is a diagrammatic view of the male sleeve with the band 21 thereon, the yoke being partially broken away, the upper jaw 6 being shown in process of engagement with the neck and the knurled head of the male sleeve.

Figure 10 shows the complete engagement between the upper jaw and the knurled head and its neck.

2

In the drawings, like reference numerals indicate like parts.

In the drawings:

Reference numeral 1 indicates the mop stick which is ordinarily made of wood, 2 indicates the male sleeve with a thread formed thereon with a neck 3 formed on the bottom thereof and a head 4 formed on the bottom of the neck. The sleeve, the neck and the head are preferably all formed integral in one piece. The sleeve 2 is held on the stick 1 by the pin 5. In Figures 1 and 3, I have shown the upper jaw 6 which comprises two plates 6a and 6b. These plates are exactly alike. Each of these has a rectangular slot 7 formed therein in which engages the knurled head 4. Above the slot each of the plates is formed with a half round 8a and 8b. When the two plates 6a and 6b are brought together, these two half rounds engage around the neck 3 so that the upper jaw is swiveled on the neck 3. The two plates 6a and 6b are spot welded or riveted together as indicated at 9, 10, 11, 12 and 13.

On the plates 6a and 6b are formed the teeth 14 and 15 which engage the fibrous material of the mop and holds it against the yoke 16 of the mop handle.

A female sleeve 17 is provided which is mounted on the male sleeve 2 so that either of them can turn on the other. The female sleeve has female threads thereon which engage with the male threads of the male sleeve and the female sleeve is about half the length of the male sleeve. On the lower end of the female sleeve is formed the yoke 16 which yoke is made either integral with the female sleeve or is spot welded thereto. This yoke is formed with a V-shaped groove 18 which groove extends clear around the yoke. This yoke appears in Figure 4 which shows a section taken on the line 4x—4x as indicated in Figure 1. The outer end of each plate 6a and 6b of the jaw is bent half diamond shape as indicated at 19 in Figure 4. The two plates form a diamond shaped molding when brought together. This diamond shaped end 19 engages in the V-shaped groove 18 and slides up and down therein as the mop stick and the male sleeve is turned in the female sleeve. In this way the jaw 6 can be brought into engagement with the groove in the bottom of the yoke 16 or as near thereto as is necessary to clamp the fibrous material with the mop between them and the up and down movement of the jaw is secured by turning the mop stick to the left or right as the case may be.

On the bottom of the female sleeve 17, I provide a reinforcing band 21 spot welded thereto,

55

which band appears in Figure 1. It can have a female thread therein if desired or it can be left plain. On the upper end of the female sleeve I provide another reinforcing band 22 which is also shown in Figure 1. This can be threaded or left plain and when set in a predetermined position it can be spot welded or brazed in that position.

This band 22 has an irregular extension 23 formed thereon as shown in Figures 5 and 6. This extension has parallel sides which acts as a guide for a block 24 which slides in and out between the parallel sides. In the end 25 of the extension 23 is threaded a screw 26 having a head 27. The right hand end of this screw is reduced as shown at 28 in Figure 6 and is swiveled in the block 24 so that by turning the screw 26, the block 24 can be moved to the left or right as shown in Figures 5 and 6. The block is grooved so that it rides on one of the male threads of the male sleeve 2. This appears in Figure 6. By turning the knurled head a few degrees, the clamping effect of the block 24 on the male thread is released and the stick in the male sleeve can be turned and when the jaw 6 has reached its correct position, the head 27 will be turned to clamp the block 24 on the male thread and lock the male thread and the female thread together. This pushes the male sleeve over against the female sleeve and holds the two of them together against turning on each other.

It will be understood that the female sleeve is cut away to form a recess as indicated at 30 and the block 24 always remains loosely engaged with this recess, so that when the block is clamped against the male sleeve, the one sleeve cannot turn in the other sleeve.

In Figure 7 I have shown a modification of this locking device in which 1a indicates the stick, 2a indicates the male sleeve and 17a indicates the female sleeve and 22a indicates a reinforcing band which is round and does not have the extension shown in Figure 5. The male threads are left flat or mutilated to form a groove or recess on opposite sides of the male sleeve as indicated at 40 in Figure 7. The female sleeve is cut away to form a recess as indicated at 41. The band is not cut away or mutilated in any way. This band 22a is spot welded to the female sleeve 17a and turns with it. When the groove 40 formed by the mutilation of the male threads is brought into line with the recess 41, the key 42 can be put into the grooves 40, 41 thus locking the male sleeve and the female sleeve against turning on each other. It is obvious that because the groove 40 is formed on both sides of the sleeve 2a that a half turn of the stick will bring the groove 40 into line with the recess at 41 so that the male sleeve and the female sleeve can be keyed or locked together.

The male sleeve 2, neck 3 and knurled head 4 are formed in one piece. The female sleeve 17 and yoke 16 are formed in another. The jaws 6a and 6b are brought together and set diagonally in the V-shaped groove 18 of the yoke 16. See Fig. 8. If necessary the yoke can be cut away at the lower left hand corner and the upper right hand corner to permit this to be done. They are then brought into horizontal position as shown in dotted lines in Figure 8, and at the upper end they are spread apart and passed over the knurled head 4 and brought together around the neck 3, it being understood that the male sleeve would then be threaded into the female sleeve and brought to the po-

sition shown in Figure 1 or 9. The two plates 6a and 6b would then be closed around the neck 3 and would be welded together, as shown in Figure 10. The rings 21 and 22 can be put in place on the female sleeve either before or after the above operation.

Having assembled the mop handle in this way and having fixed the mop stick in the male sleeve, the jaw can be moved up, the fibrous material can be fixed in place in the mop handle over the yoke 16, and the jaw 6 can be moved down to engage this fibrous material. Thereafter the sleeves can be clamped together as above described. The mop is then ready for use. If it is desired to remove the fibrous material and renew it with fresh material it can be done by reversing this process.

I claim:

1. In a mop holder and handle therefor, the combination of a handle, a metal sleeve, a pin fastening said sleeve on said handle, a male thread formed on said sleeve, a stem formed on the bottom of said sleeve and a head formed on the end of the stem, a jaw comprising two similar plates clamped together each of said plates having a half round formed thereon, which half rounds when the plates are clamped together form a collar that is swiveled on said stem and held in place by said head, a second sleeve having a female thread formed thereon, engaging with the male thread on said first named sleeve, a yoke formed on said second sleeve extending below said jaw, V-shaped grooves formed in the sides of said yoke in which the sides of said jaw engage, said jaw being moved up and down in said grooves by the turning of the handle and the first named sleeve in the second named sleeve, means for locking the two sleeves together.

2. In a mop holder and handle therefor, the combination of a handle, a metal sleeve, a pin fastening said sleeve on said handle, a male thread formed on said sleeve, a stem formed on the bottom of said sleeve and a head formed on the end of the stem, a jaw comprising two similar plates clamped together each of said plates having a half round formed thereon, which half rounds when the plates are clamped together form a collar that is swiveled on said stem and held in place by said head, a second sleeve having a female thread formed thereon engaging with the male thread on said first named sleeve, a yoke formed on said second sleeve extending below said jaw, V-shaped grooves formed in the sides of said yoke in which the sides of said jaw engage, said jaw being moved up and down in said grooves by the turning of the handle and the first named sleeve in the second named sleeve, the two sides of the jaw being formed V-shaped in cross section.

3. In a mop holder and handle therefor, the combination of a handle, a metal sleeve, a pin fastening said sleeve on said handle, a male thread formed on said sleeve, a stem formed on the bottom of said sleeve and a head formed on the end of the stem, a jaw comprising two similar plates clamped together each of said plates having a half round formed thereon, which half rounds when the plates are clamped together form a collar that is swiveled on said stem and held in place by said head, a second sleeve having a female thread formed thereon, engaging with the male thread on said first named sleeve, a yoke formed on said second sleeve extending below said jaw, V-shaped grooves formed in the sides of said yoke in which the

sides of said jaw engage, said jaw being moved up and down in said grooves by the turning of the handle and the first named sleeve in the second named sleeve, a ring surrounding the female sleeve said ring having a rectangular extension on one side thereof, a screw threaded in said extension radial to the sleeves, a block mounted to slide in said extension and engaged by said screw and being adapted to draw the female sleeve against the male sleeve and hold the sleeves from turning in each other.

THOMAS W. HEALY.
